UNITED STATES PATENT OFFICE.

WILLIAM CLARENCE O'BRIEN, OF CANTON, OHIO, ASSIGNOR TO CENTRAL ALLOY STEEL CORPORATION, OF NEW YORK, N. Y., A CORPORATION OF NEW YORK.

ELECTRIC HAMMER.

Application filed July 27, 1922. Serial No. 577,860.

The present invention relates to improvements in electrically operated drop hammers and has particular application to a doubler for use in rolling mills for doubling the packs of sheets.

The objects of the invention are to provide a hammer having a reciprocating head with a solenoid for assisting the force of gravity in driving the head downward and with a pair of solenoids wired in parallel, for raising the reciprocating head, automatically, operating means being provided for reducing the current to the lifting solenoids, as the head reaches the upper limit of its movement, it being obvious that less power is required to hold the head in the raised position than is required to raise the head from its lowered position.

The above and other objects may be attained by constructing the hammer in the form illustrated in the accompanying drawings, in which—

Figure 1 is a side elevation of a hammer embodying the invention, showing the head in the lowered position;

Fig. 2, a longitudinal sectional view through the hammer, showing the head in the raised position; and

Fig. 3, a diagrammatic view of the wiring. Similar numerals indicate corresponding parts throughout the drawings.

The base 1 of the hammer is preferably formed of metal and arranged to be mounted flush with the floor of the mill, in order that the packs of sheets may be slid into position thereon. Standards 2 are rigidly mounted upon the base near opposite ends thereof and provided with the guideways 3 in which the reciprocating head 4 is slidably mounted, said head being preferably formed of iron and provided upon its under face with a plate 5 of brass or other non-magnetic material.

The standards 2 are joined together at their upper ends by a cross plate 6 upon the ends of which are mounted uprights 7 which are connected at their upper ends by a cross plate 8, both of said cross plates being formed of iron or other suitable metal.

A central solenoid 9 for the purpose of forcing the head downward, and a pair of solenoids 10 for the purpose of raising the head and holding the same in the raised position.

are located between the plates 6 and 8, being clamped in position therebetween by means of the nuts 11 upon the upper screw threaded ends of the rods 7.

The solenoids 9 and 10 are insulated from the plates 6 and 8 as indicated at 12 and the solenoids 10 are wired in parallel as shown in the drawings. The plates 6 and 8 are provided with the openings 13 to receive the cores 14 and 15 of the solenoids 9 and 10 respectively, said cores being connected to the upper side of the reciprocating head 4.

These cores are, of course, formed of iron, the core 14 being connected to the reciprocating head by means of a rod 16 of brass or other non-magnetic material, for the purpose of obtaining the maximum force of the blow, the core naturally moving to the center of the solenoid when the same is energized.

As shown in diagram in Fig. 3, the lifting and holding solenoids 10 are connected in parallel, the terminals thereof being connected together as by the wires 17 and 18, the wire 17 being connected to the lead wire 19 by the wire 20 and the wire 18 being connected to the lead wire 21 by the wire 22. The solenoid 9 is connected to the lead wire 19 by a wire 23, and to the lead wire 21 by a wire 24, a manually operated switch 25 controlling the circuits to the solenoids 9 and 10, indirectly through the relays 34 and 35, being so arranged that one of said circuits is closed as the other is opened.

Each of the relays 34 and 35 have an armature 36 carrying a blade 37 arranged to close the primary circuit when the secondary or relay circuit is energized.

A bracket 26 is mounted upon the upper plate 8 and carries a fixed contact 27 located in the circuit to the solenoids 10, a movable contact 28 being carried upon an arm 29 pivoted as at 30 to the bracket and having a depending portion 31 which carries a roller 32 arranged to be engaged by the core 14 when the head is in the raised position, whereby the arm 29 is tilted, breaking the direct circuit to the solenoids 10, causing the current to pass through the resistance element 33, thus materially lowering the current passing through the solenoids 10.

It will be seen that this device is affected only as the head reaches the upper limit of

its stroke, at which time less current will be required to hold the head in the raised position than was required to raise the head from the lowered position, thus providing for a material saving in the current required to operate the hammer.

The operation of the device may be set forth as follows: in its normal position, the switch 25 will close the circuit to the relay 35 thereby closing the circuit to the solenoids 10 and the circuit through the contacts 27 and 28 will be broken, deenergizing the relay 38 and causing the current to flow through the resistance element 33 to the solenoids 10, furnishing only sufficient current to said solenoids to hold the reciprocating head in the raised position.

When the switch 25 is operated to close the circuit to the relay 34 thereby closing the circuit to the solenoid 9, the circuit to the solenoids 10 is broken, releasing the hammer and forcing the same downward upon the pack which has been placed in position upon the base 1. The core 14 is so located with reference to the reciprocating head that the head will contact with the pack just before the core reaches the center of the solenoid 9, thus obtaining the full force of the blow as the solenoid has a natural tendency to draw the core to the center of its field, thus causing the reciprocating head to strike the pack when it is traveling at the highest rate of speed.

The plate 5 upon the bottom of the reciprocating head being of non-magnetic material, the pack of sheets will not be attracted by the head as it is raised. After the head has reached its lower position, the switch 25 is operated to break the circuit to the solenoid 9 and close the circuit to the solenoids 10, energizing the same and through the cores 15, raising the reciprocating head.

As the head reaches its raised position, the core 14 will engage the roller 32 upon the arm 29, rocking said arm outward and breaking the circuit through the contacts 27 and 28 and the relay 38 which opens the circuit to the solenoids 10, causing the circuit to pass through the resistance element 33 to said solenoids, thus reducing the current and furnishing the solenoids 10 with only sufficient current to hold the reciprocating head in the raised position.

By wiring the solenoids 10 together as illustrated, they will, together with the head, form substantially a large horseshoe magnet, and the cores 15 thereof will not have a tendency to locate in the center of the field as in the case of an ordinary solenoid. With this construction, the sudden reduction of the current to the lifting solenoids, as the head reaches the raised position, has a cushioning effect upon the head, preventing the same from striking a hard blow against the plate 6 and allowing the same to drop back a slight distance from said plate as shown in Fig. 2, in which position the head will be held by the reduced magnetic power of the solenoids, as it is obvious that only a fraction of the lifting power will be required to hold the head in the raised position.

I claim:—

An electrically operated hammer including a reciprocating magnetic head, a solenoid for assisting in effecting the working stroke of the head, a pair of solenoids wired in parallel for lifting the head and holding the same in the raised position, magnetic cores carried by the head and extending through the lifting solenoids, and means for automatically reducing the current to the lifting solenoids as the head reaches its upper position.

WILLIAM CLARENCE O'BRIEN.
